(57) **CLAIM**

The ornamental design for an end cap coping for swimming pool, as shown and described.

DESCRIPTION

FIG. 1 is a perspective view of an end cap coping for swimming pool showing my new design;

FIG. 2 is a top view thereof;

FIG. 3 is a bottom view thereof;

FIG. 4 is a front view thereof;

FIG. 5 is a rear view thereof; and,

FIG. 6 is a side view thereof, the opposite side view being substantially identical.
